UNITED STATES PATENT OFFICE.

MILLER HALL, OF CHICAGO, ILLINOIS.

DESIGN FOR A BEDSTEAD.

SPECIFICATION forming part of **Design No. 27,489, dated August 3, 1897.**

Application filed June 23, 1897. Serial No. 641,997. Term of patent 7 years.

To all whom it may concern:

Be it known that I, MILLER HALL, a citizen of the United States, residing at Chicago, county of Cook, and State of Illinois, have invented and produced a new and original Design for Bedsteads, of which the following is a specification, reference being had to the accompanying drawing, which shows a perspective view of a bedstead embodying my design.

As shown, the leading or material feature of my design consists of such a conformation of the foot portion of the bed that the same is curved to form two equal bays or bows A', separated by an intermediate vertical post B. At the sides of the bays or bows, which

are formed by the curvature of the two lateral halves of the foot portion of the bedstead, around parallel vertical axes internal thereto, are the vertical posts B' B².

The posts B B' B² may be suitably ornamented, and the panels composing the bays or bows are of open-work, which may also be suitably ornamented.

What I claim is—

The design for a bedstead, substantially as herein shown and described.

MILLER HALL.

Witnesses:

FREDERICK C. GOODWIN,
IRVINE MILLER.
